[57] CLAIM

The ornamental design for an electronic baseball game casing, substantially as shown.

DESCRIPTION

FIG. 1 is a top perspective view of the electronic baseball game casing showing our new design.

FIG. 2 is a top plan view thereof;

FIG. 3 is a left side elevational view showing the bottom thereof, the right side view being a mirror image of the left side view.

FIG. 4 is a front view thereof;

FIG. 5 is a bottom plan view;

FIG. 6 is a rear elevational view thereof.
